STRETCHING APPARATUS

Victor H. Hasselquist, Akron, Ohio, assignor to
 The B. F. Goodrich Company, New York, N. Y.,
 a corporation of New York

Application June 14, 1945, Serial No. 599,490

5 Claims. (Cl. 254—69)

1

This invention relates to apparatus for stretching sheet material and is especially useful for stretching elastic covers such as ice-removing covers about or along the surfaces of airfoils.

Elastic ice-removing covers have been secured about the leading edges of the wings and other parts of aircraft by rows of hollow tubular rivets secured to the skin of the airfoil and having threaded bores for securing screws. The covers have been provided with rows of apertures along their margins for receiving fastening screws adapted to enter the threaded bores of the rivets, and fairing strips of sheet material, also having apertures for engaging the same screws, sometimes have been applied over the margins of the covers.

Stretching of the covers to secure them in place under tension without damage to the covers or to the surfaces to be covered has been a difficult problem, especially where the parts are of large size. Where ice-removing covers are to be applied these have often had air connections integral therewith which had to be inserted through apertures therefor in the skin of the airfoil causing further difficulties in assembly. By the present invention an improved apparatus is provided for facilitating the assembling operation. The apparatus is also useful wherever a covering is to be stretched along a surface to which it is to be attached.

Objects of the invention are to provide uniform stretching of a margin along a surface; to provide for permitting the application of one margin of the covering in advance of entry of the air connections; to provide for application of the cover at any position or attitude of the airfoil; to provide for clamping the margin and uniformly stretching the covering from one end of the covering to the other, and to provide for applying the cover with the least amount of manual exertion.

These and other objects will appear from the following description and the accompanying drawings.

Of the drawings:

Fig. 1 is a perspective view of a portion of an airplane showing an ice-removing covering attached to the leading edge of the wing, parts of the plane being broken away.

Fig. 2 is a perspective view of a section of the leading edge of the wing showing one margin of the covering secured thereto and showing one form of clamping mechanism for clamping the opposite margin of the covering preparatory to stretching the covering in place.

Fig. 3 is a similar view showing the stretching

2

apparatus secured to the wing and to the clamping means in position to stretch the covering about the leading edge of the wing.

Fig. 4 is a similar view showing the covering stretched into place and temporarily secured by holding pins, the stretching apparatus being also shown as removed from the covering and from the wing.

Fig. 5 is a detail perspective view of a portion of the clamping means.

Fig. 6 is a sectional view of the stretching and clamping means showing a portion of the wing and in dot and dash lines the covering, other parts being broken away, the section being taken along line 6—6 of Fig. 6A.

Fig. 6A is a similar view of a portion thereof drawn to a larger scale.

Fig. 6B is a sectional view taken on line 6b—6b of Fig. 6.

Fig. 7 is a side elevation of a pin for holding the stretching means in place on the surface to be covered.

Fig. 8 is a side elevation partly in section of a modified clamping means.

Fig. 9 is a detailed view of a movable jaw and cam bar thereof.

Fig. 10 is a section taken on line 10—10 of Fig. 8.

Fig. 11 is a side view partly in section of another modification of the clamping means.

Fig. 12 is a detailed view thereof.

Fig. 13 is a sectional view taken on line 13, 13 of Fig. 11.

Referring to the drawings and first to Figs. 1 to 7 thereof, which show a form of apparatus constructed in accordance with and embodying the invention, the numeral 10 designates the skin of the plane about which the stretchable covering 11 is to be applied. As shown in Figs. 2, 3 and 4, one margin 12 of the covering has been secured to the wing by screws 13 passing through apertures in said margin and entering the threaded apertures of hollow threaded rivets 14 secured to the skin of the wing. A fairing strip 15 has also been applied over the margin and is held by the same screws. The opposite margin 16 of the covering is secured to a clamping means 17 which extends the length of the covering and grips the margin throughout its length by clamping pressure. Removably secured to the wing by pins 18 entering some of the apertures of a row of apertures 19 extending along the wing at the position of desired attachment of the unsecured margin are a plurality of stretching

means 20 as seen in Fig. 3. The stretching means

are also detachably secured to the clamping bar 17 for the purpose of drawing the covering into fastening position.

Referring to Fig. 5 which shows one form of clamping means 17 constructed in accordance with the invention, this includes a tubular bar 25 of generally rectangular cross-section and having a longitudinal opening 24 along one lower corner thereof. The lower side of the hollow bar, designated 26, acts as a fixed jaw against which the beaded reinforced margin 16 of the covering 11 is clamped by a movable jaw 27 in the form of a bar extending loosely through the hollow enclosure of the bar 25. A third bar 28 extends through the hollow enclosure of the bar 25 between it and the movable bar 27. The bar 28 is of substantial semi-circular cross-section and when rotated acts as a cam to force the movable jaw 27 against the fixed jaw 26, this being due to the semi-circular form of the bar which in one rotative position has its flat side facing the inner face of the bar 25 opposite to the jaw 26 and thereby releases pressure against the movable jaw 27, whereas in another rotative position, shown in Figs. 5 and 6, it presents greater depth and wedges the movable jaw 27 against the fixed jaw. Rotation of the cam bar 28 may be accomplished by a handle 29 fixed to the bar at its flat side and extending through a clearance notch 30 in the wall of the bar 25. A fixed handle 31 may be secured to bar 25 adjacent the handle 29 to assist in rotating the bar 28, the arrangement being such that the operator may grasp both handles with one hand for application of clamping pressure.

Referring to Fig. 6 which shows the stretching means in section, this comprises a bar 35 having an angular foot 36 fixed thereto, the foot having a pin 18 extending therefrom adapted to enter the threaded aperture of a hollow rivet 38 to which the margin 16 is to be attached. A carriage 39 is slideably mounted upon bar 35 and for this purpose is provided with a friction block 40 secured thereto as by screws 37 and having an aperture 41 adapted to pass over the bar 35. The carriage 39 is formed with a clearance opening 42 about the rod 35. A second friction block 43 has an aperture 44 for receiving the bar 35 therethrough and is mounted in a U-shaped stirrup 45 having a handle 46 attached thereto. The stirrup 45 is pivoted as at a pin 47 to the block 43. A coil spring 48 mounted between the carriage 39 and the block 43 urges the block 43 normally to the left as seen in Fig. 6 and thereby causes the block 43 to frictionally clamp the bar 35.

For facilitating free movement of the block 43 along the rod 35 in one direction while providing for gripping of the rod when the block is urged in the opposite direction by the movement of a force applied at a position spaced-apart from the center line of the rod 35, the aperture 44 is formed with a chamfer 50 at its upper left-hand side and a chamfer 51 at its lower right-hand side as seen in Figs. 6 and 6A, the arrangement being such that when a force is applied along the rod 35 at the pivot pin 47 in a direction to the right of Figs. 6 and 6A, the corners, provided by the intersections of the chamfers 50, 51 with the walls of the aperture 44, will frictionally grip the rod and prevent movement along the rod, and when such force is applied at the pivot pin 47 in a direction to the left of Fig. 6, pressure on the corners will be relieved and a long bearing surface of the aperture 44 will be presented to the

rod 35 permitting sliding movement of the block along the rod. The aperture 41 of the block 40 is similarly formed with a chamfer 52 at its upper left side and a chamfer 53 at its lower right side which provide for gripping of the rod 35 by the block 40 when a superior force is applied to the block 40 at a position near the pivot pin 55 as by pressure of the clamping bar 25 due to tension of the covering in the direction to the right of Fig. 6, and permitting sliding of the block 40 along the rod in a direction to the left of Fig. 6 when a superior force is applied at the pivot pin 55 acting in a direction to the left of Fig. 6. The legs of the stirrup 45 are pivotally connected as at 56 at a position less remote from the handle 46 than pivot pin 47 to a pair of links 57 which in turn are pivotally connected to the block 40 at the pivot pin 55. The carriage 39 is formed with a horizontal extension 58 parallel to the rod 35 and terminating in a downwardly projecting portion 59. The arrangement is such that the projecting portion 58, the portion 59 and the block 40 provide a notch adapted to confine the clamping bar 25 with one face of the bar resting against the block 40 near the pivot pin 55.

When the pin 18 secured to the rod 35 is engaged in an aperture in the skin of a plane and the clamping bar 25 is engaged in the notch of the stretching means with the margin 16 of the covering clamped by the clamping means, the carriage 39 may be shoved along the bar 35 in a direction to the left of Fig. 6 until the covering is under slight tension. This movement may readily be accomplished by hand manipulation. With the covering slightly tensioned, a force will be applied to the block 40 in a direction to the right in Fig. 6 in the region of the clamping means or near the pivot pin 55, thereby tipping the stretching means slightly with relation to the rod 35 and causing the block 40 to grip the rod. Further tensioning of the covering may then be accomplished by first moving the handle 46 to the right which will cause the handle to pivot about the pivot pin 56 and to apply a force in a direction to the left at the pivot pin 47 to the block 43. This will move the block 43 bodily to the left in Fig. 6 along the rod 35 to a new position. Movement of the handle 46 is then reversed and pressure applied thereon in a direction to the left whereupon the block 43 will grip the rod 35 under the off-center pressure of the spring 48 and handle 46 will pivot about the pivot pin 47 thereby moving links 57 to the left of Fig. 6 which in turn will overcome the gripping force due to the tension of the covering and move the block 40 and with it the carriage 39 to the left to a new position with further tensioning of the covering. In other words by reciprocating the handle 46, a walking movement of the blocks 40 and 43 along the rod 35 is provided, and the covering is drawn into a position where the apertures in its margin coincide with the apertures in the skin of the plane and screws or temporary studs may then be inserted through the apertures of the covering and through the apertures of the skin of the plane to hold the covering in place.

As shown in Figs. 2 to 4 a plurality of clamping means may be distributed along the clamping bar so as to apply tension at a plurality of positions simultaneously and by substantially simultaneous operation of the stretching means the margin of the covering may be drawn into position in a single operation without damage to the covering such as might result by local stretching. When the covering has been secured by screws,

the tensioning means may be released by applying a tipping force to the carriage 39 as by tapping it with a hammer or applying such movement by use of a lever or a wrench applied to the carriage. This may conveniently be accomplished by a stop-pin 60 on the carriage adapted to contact the stirrup 45 when the handle 48 is moved to the right in Fig. 6 beyond such movement as is necessary to accomplish the walking movement.

The pin 18 which holds the boot 36 of the rod 35 to the threaded aperture of the rivet 33 may be constructed as shown in Fig. 7 wherein the pin comprises a portion 51 of such small diameter as to pass endwise through the threaded aperture and having threads 62 on one side of the pin adapted to be engaged by the threads of the rivet when the pin is moved in a direction toward such threads. Such a pin has threaded engagement with the rivet at the side toward the tensioned covering and prevents slipping of the tensioning means from the covering of the plane.

Referring to Figs. 8 to 10, which show a modified form of clamping means, a tubular bar 65 of rectangular cross section and having a longitudinal opening 66 along one corner thereof encloses a pair of bars 67, 68 extending longitudinally thereof. Bars 67, 68 have complementary saw-tooth cam surfaces 69, 70 respectively. Bar 67 is formed with a movable jaw 67a and the tubular bar 65 is formed with a cooperating fixed jaw 71. The two jaws are adapted to grip the margin of a covering preferably back of a beaded edge thereof and are so formed as to provide a clearance space 72 therebetween for receiving such beaded edge. The cam surfaces of the bar 67, 68 are so inclined that relative movement of one of the bars longitudinally of the other will cause their cam surfaces to force the bars apart when the movement is in one direction and will permit them to move toward each other when the movement is in the opposite direction. Such relative movement is provided for by screws 73, 74 which engage threaded openings 75, 76 respectively in opposite ends of the bar 68. The enlarged heads of these screws are adapted to overlap and engage the ends of the bar 67. The arrangement is such that by turning the screw 73 in a direction to enter the threaded opening 75 the movable jaw 70 will be moved toward the fixed jaw 71 and will grip the margin of the covering. When the covering is to be released the screw 73 may be screwed outwardly and the screw 74 may be screwed into the aperture 76 and its enlarged head engaging the bar 67 will force the bar down the inclined cam surface moving the movable jaw 70 away from the fixed jaw 71 and releasing the covering.

Referring to Figs. 11 to 13 of the drawings which show a still further form of clamping means, this apparatus is provided with a tubular bar 80 of rectangular cross section having a longitudinal opening 81 near one corner thereof, the tubular bar providing a stationary jaw 82 therealong adjacent the opening. Mounted within the hollow passage of the tubular bar 80 for movement with respect thereto are a pair of bars 83, 84 having cooperating cam projections 85, 86 thereon at intervals along their length. The bar 84 is formed with a movable jaw 87 adapted to cooperate with the fixed jaw 82 in clamping the margin of the covering, the jaws also being formed to provide a clearance cavity 88 therebetween back of the jaws for receiving the beaded margin of the covering.

When the bar 83 is moved longitudinally of tubular bar 80 with respect to bar 84, the cam projections 85 engage the cam projections 86 and force the movable jaw toward the fixed jaw. 5 For providing such movement the tubular bar 80 is formed with a slot 90 therethrough through which a block 91 attached to the bar 83, as by screws 92, is adapted to project. A lever 93 is pivotally mounted as at 94 to the block 91. A 10 pair of links 95 are pivotally secured to the lever 93 at 96 and their other ends are pivotally secured as at 97 to a lug 98 fixed to the bar 80 adjacent the slotted opening 90. The arrangement is such that when the lever 93 is moved to the 15 left in Fig. 11 to its full line position the block 91, and with it the cam bar 83, is moved to the right as shown in Fig. 11, thereby forcing the movable jaw 87 toward the fixed jaw 82 and clamping the fabric, and when the lever 93 is moved to the 20 dot and dash line position of Fig. 11, the block 91, and with it the cam bar 83, are moved to the left of the figure to the dot and dash line position, thereby releasing the margin of the covering.

These and other variations may be made without departing from the invention as it is defined by the following claims.

I claim:

1. Apparatus for stretching a covering having marginal apertures to a desired position upon a surface having corresponding apertures at said position for receiving fastening means for securing the covering thereto, said apparatus comprising a rod having means for attaching it to said surface at said desired position, including an element insertable in one of the apertures of said surface, with the rod extending toward a margin of the covering to be attached at said position, a clamping bar arranged to extend along said margin and having means to grip an extensive portion of the margin of said covering and means movable along said rod and engageable with said clamping bar for stretching said covering to said position.

2. Apparatus for stretching a covering having marginal apertures to a desired position upon a surface having corresponding apertures at said position for receiving fastening means for securing the covering thereto, said apparatus comprising a rod having means for attaching it to said surface at said desired position, including an element insertable in one of the apertures of said surface, with the rod extending toward a margin of the covering to be attached at said position, a clamping bar arranged to extend along said margin and having means to grip an extensive portion of the margin of said covering and means movable along said rod and engageable with said clamping bar for stretching said covering to said position, said means to grip the margin of the covering comprising jaws engageable with a substantial portion of said margin, and cam means for moving one of said jaws toward the other.

3. Apparatus for stretching a covering having marginal apertures to a desired position upon a surface having corresponding apertures at said position for receiving fastening means for securing the covering thereto, said apparatus comprising a rod having means for attaching it to said surface at said desired position, including an element insertable in one of the apertures of said surface, with the rod extending toward a margin of the covering to be attached at said position, a clamping bar arranged to extend along said margin and having means to grip an extensive portion of the margin of said covering and means

movable along said rod and engageable with said clamping bar for stretching said covering to said position, said means movable along said rod comprising a carriage slideable along said rod, and means on said carriage for advancing it along said rod in step-by-step movements.

4. Apparatus for stretching a covering having marginal apertures to a desired position upon a surface having corresponding apertures at said position for receiving fastening means for securing the covering thereto, said apparatus comprising a rod having means for attaching it to said surface at said desired position, including an element insertable in one of the apertures of said surface, with the rod extending toward a margin of the covering to be attached at said position, a clamping bar arranged to extend along said margin and having means to grip an extensive portion of the margin of said covering, and means movable along said rod and engageable with said clamping bar for stretching said covering to said position, said means movable along said rod comprising a carriage, a plurality of gripping members on said carriage adapted to frictionally grip said rod, and means on said carriage for alternately advancing said gripping members.

5. Apparatus for stretching a covering having marginal apertures to a desired position upon a surface having corresponding apertures at said position for receiving fastening means for securing the covering thereto, said apparatus comprising a rod having means for attaching it to said surface at said desired position, including an ele-

5
